UNITED STATES PATENT OFFICE.

PAUL J. DONAVAN, OF DENVER, COLORADO.

SPARK PLUG.

1,418,632.

Specification of Letters Patent. Patented June 6, 1922.

Application filed January 20, 1920. Serial No. 352,837.

To all whom it may concern:

Be it known that I, PAUL J. DONAVAN, a citizen of the United States, residing at the city and county of Denver and State of Colorado, have invented certain new and useful Improvements in Spark Plugs; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 My invention relates to improvements in spark plugs, my object being to provide a device of this character which shall be of such construction as to protect the porcelain or insulating member as far as possible from 20 breakage or injury due either to the use of a wrench in manipulating the nut which holds the parts of the plug in the assembled relation or in securing the electrical conductor to the plug.

25 My further object is to protect the porcelain or insulating member so far as possible from unequal heating. It is well known that in spark plugs of ordinary construction the porcelain member is so exposed that it is 30 easily broken in case a wrench slips while assembling the parts of the plug, or when a tool of this character is otherwise used in connection therewith. It is also well known that the porcelain member of the ordinary 35 spark plug is so arranged that a part of it is exposed to the intense heat of the combustion chamber, while the other part is located outside of the cylinder and is entirely unprotected from atmospheric temperature, 40 thus exposing the porcelain member to unequal temperature conditions, which often results in cracking.

45 My improvement consists in shortening the porcelain, whereby the upwardly projecting neck of small diameter is done away with, and the upper portion of the plug made relatively large, and its exposed portion rounded and covered by a washer composed of fiber or other suitable material. The 50 bushing nut, which is screwed into the metal body portion of the plug directly engages this fiber washer, and when properly adjusted holds the parts of the plug securely in the assembled relation. Furthermore, the stem 55 of the plug is divided, the main portion being securely mounted in the porcelain and carry-

ing a sleeve with which the upper portion, which extends beyond the porcelain, is detachably connected. By virtue of this construction, there is no danger of loosening 60 the stem from the porcelain by tightening the nut which holds the electrical conductor in place, since while so doing there is no twisting strain on the body of the stem, or the part which is securely connected with the 65 porcelain or insulating member.

Having briefly outlined my improvement, I will proceed to describe the same in detail, reference being made to the accompanying drawing, in which is illustrated an embodiment thereof. In this drawing:

Fig. 1 is an elevation of my improved spark plug.

Fig. 2 is a vertical longitudinal section of the same.

Fig. 3 is a similar view, showing the upper portion of the stem detached from the porcelain member and from the cooperating stem portion.

The same reference characters indicate the 80 same parts in all the views.

Let the numeral 5 designate the metal body of the plug, whose lower portion is threaded, as shown at 6, for connection with the cylinder of the engine. The insulating member 7 has a rounded or convex upper surface, which is covered by a washer 8, preferably composed of fiber and engaged by a bushing nut 9, which is exteriorly threaded to cooperate with the interior 85 threads of the metal body part 5 of the plug, the bushing nut being interiorly curved to correspond with the curvature of the outer surface of the insulating member. As the upper portion of the last named member is 90 relatively thick or heavy and its exposed portion curved and protected by the washer 8, there is practically no danger of breakage by the slipping of a wrench, either when connecting the plug with the engine or while 100 screwing the bushing nut into place, or when tightening the nut 10, which connects the electrical conductor with the stem.

The upper central portion of the porcelain member 7 is provided with a recess 12, surrounded by a sleeve 13, which is cast or moulded in the porcelain member, the lower portion of the sleeve being further permanently connected with the body 14 of the stem, which extends downwardly through an 110 opening in the porcelain, its lower extremity constituting an electrode which cooperates

with a second electrode 15, which is connected with the metal body member 5. The sleeve 13 is exteriorly beaded, as shown at 16, to form an interior circumferential 5 groove adapted to receive an exterior bead 17 formed on the detachable part 18 of the stem, whose lower portion is slotted, as shown at 19, to permit slight contraction while inserting the member 18 in the recess 10 12. As soon as this member is pushed into the recess 12 to its limit of movement, the bead 17 will spring outwardly into the interior groove of the sleeve 13, whereby the two stem parts are interlocked and constitute 15 for all practical purposes an integral device.

It will be understood that when in use an electrical conductor (not shown) is connected with the part 18 of the stem, between 20 a collar 20 formed on the said part, and a top nut 10, which is interiorly threaded to cooperate with the threaded part 22. It will be understood that when tightening the nut 10 there is no twisting strain on the body 25 part 14 of the stem, which would have a tendency to loosen the stem or break it away from the porcelain member with which it must be securely connected. It will thus be understood that the part 18 of the stem is 30 readily attachable and detachable from its cooperating stem member and from the insulating or porcelain part 7. Suitable gaskets 23 are arranged between the inclined shoulders on the porcelain member 7, and opposing shoulders on the metal body part 5 35 of the plug, thus giving a cushioning effect

while at the same time holding the elements in suitable cooperative relation.

Attention is also called to the fact that by reason of the divided stem and the resilient 40 inner portion of the member 18, a considerable degree of flexibility is provided for without in any way interfering with the function of the stem as an electrical conductor. By virtue of this feature liability 45 to breakage of the parts, or disturbance of the proper cooperative relation between the elements of the stem is to a large extent obviated or minimized. The stem member 14, as well as the sleeve 13, is cast permanently in 50 the porcelain member.

I claim:

1. A spark plug, whose insulating member is convexly curved exteriorly, a fiber washer covering said curved part of said member, 55 and a bushing nut threaded into the metal body and concaved to conform to the curvature of the adjacent part of the insulating member, and arranged to engage said washer.

2. In a spark plug, a body, an insulating porcelain therein, a bushing threaded into the body to retain the porcelain and through which the porcelain is exposed, said porcelain being short so that its top is approximately flush with the top of the bushing, whereby the porcelain is protected from injury by blows, and a protecting washer on the upper portion of the porcelain for further protection thereof. 65

In testimony whereof I affix my signature.
PAUL J. DONAVAN. 70
